MOBILE HOME TIE-DOWN TENSIONING BRACKET

Joseph H. Manning, 57045 Mayflower Road,
South Bend, Ind. 46619

Filed July 22, 1974, Ser. No. 490,583

Term of patent 14 years

Int. Cl. D8—08

U.S. Cl. D8—229

Fig. 1

Fig. 2

Fig. 3

Fig. 4

Fig. 5

Fig. 6

FIG. 1 is a perspective view of a mobile home tie-down tensioning bracket embodying the present design;

FIG. 2 is an elevational view of the tie-down tensioning bracket;

FIG. 3 is an elevational view of the side of the bracket opposite that shown in FIG. 1;

FIG. 4 is a top plan view;

FIG. 5 is an elevational view of the side opposite that shown in FIG. 2; and

FIG. 6 is an elevational view of the bottom.

I claim:

The ornamental design for a mobile home tie-down tensioning bracket, substantially as shown.
